UNITED STATES PATENT OFFICE.

FRANK WERNER AND RICHARD OEHMIGEN, OF MINNEAPOLIS, MINNESOTA.

SAND-BAND.

SPECIFICATION forming part of Letters Patent No. 406,073, dated July 2, 1889.

Application filed April 8, 1889. Serial No. 306,418. (No model.)

To all whom it may concern:

Be it known that we, FRANK WERNER and RICHARD OEHMIGEN, both of Minneapolis, Hennepin county, Minnesota, have invented 5 certain new and useful Improvements in Sand-Bands for Vehicle-Wheel Hubs, of which the following is the specification.

Our invention relates to the hubs of wheels of ordinary highway-vehicles, and its object 10 is to provide means to prevent sand from working into the axle-boxes of the wheels and the waste oil or grease from oozing out of them; and it consists, generally, in the construction and combination hereinafter described, and 15 particularly pointed out in the claims.

In the drawings, forming part of the specification, Figure 1 is a central longitudinal section of a wheel-hub fitted with our improved sand-bands. Figs. 2, 3, 4, 5, 6, and 7 20 are details.

In the drawings, 2 represents the body of the hub.

3 is the axle-box, secured in the hub in the usual manner, and 4 is the axle, of ordinary 25 form and material.

5 is the axle-nut, adapted to bear, preferably, against the end of the box 3, and to fit into a suitable recess in the end of the hub. 6 and 7 are the hub-bands, fitted, respect- 30

ively, on the outer and inner ends of the hub. They are screw-threaded on their outer surface, and are preferably provided with a series of points or spurs 10, which are adapted to be driven into the shoulder 11 of the hub, and 35 to firmly secure the band in place.

The sand-band 8 has a closed or solid end, and fits over and entirely closes the opening in the outer end of the hub, and its inner surface is screw-threaded to engage with 40 and mesh with the threads on the outer surface of the hub-band. The outer end of the sand-band 8 is preferably flanged or cup-shaped, and is provided with a central projection or head 12, corresponding perfectly 45 in form and size to the nut 5, by means of which the sand-band 8 may be screwed and unscrewed with the same wrench that is used for the nut 5. The flanges 13 preferably project the same distance as the head 50 12, and serve to give an ornamental finish to the hub. The sand-band 9 has its inner

surface similarly screw-threaded to engage with the hub-band 7. The interior of its outer end is preferably flaring, to afford room for it to project over the axle-bed without 55 touching it and to prevent an entrance of sand to the shoulder 14 of the axle. In each of the sand-bands 8 and 9 there is preferably an annular space 15 between the end of the hub and the closed end of the band 60 and the shoulder 17 of the band 9, which serves as a receptacle for the waste oil and grease which oozes out of the axle-box, and which with the ordinary construction smears the end of the hub. 65

In order to easily screw and unscrew the sand-band 9, we prefer to cut into its projecting edge opposite rectangular notches or slots 16, and to shape the handle of vehicle-wrench to fit into these slots and to serve as 70 a lever to turn it in the desired direction. A wheel-hub fitted with these bands is fully as ornamental as with the ordinary band, and can be slipped on or off the axle without moving the band 9, which nevertheless 75 perfectly protects the shoulder 14 from contact with sand and mud. The band 8 is preferably either right or left threaded to correspond with the direction of thread on the inclosed nut. 80

We claim as our invention—

1. In a wheel-hub, the combination, with the end hub-bands 6 and 7, having their outer surface screw-threaded, of the bands 8 and 9, having their inner surface screw- 85 threaded and adapted to surround and engage with the bands 6 and 7, respectively, the band 8 having a closed end and the band 9 a flaring and open end, and both bands formed with the recesses 15 to form waste-oil 90 receptacles, substantially as described.

2. The combination, with a wheel-hub, of the screw-threaded bands 6 and 7, provided with the spurs 10, of the closed screw-threaded band 8, adapted to fit upon and engage with 95 the band 6 and having the flange 13 and the head 12 inclosed by said band, and the screw-threaded band 9, adapted to fit upon and engage with the band 7 and provided with the shoulder 17 and the slots 16, substantially as 100 described.

3. The combination, with the hub, of the

band 7, secured thereto and exteriorly screw-threaded, and the band 9, interiorly threaded to fit the threads of the band 7 and formed with an oil-space 15, and a shoulder 17 between said space and the end of the band, the portion of the band from said shoulder outward being flaring, substantially as and for the purposes set forth.

In testimony whereof we have hereunto set our hands this 3d day of April, 1889.

FRANK WERNER.
RICHARD OEHMIGEN.
